DESIGN FOR A SPOON OR OTHER ARTICLE OF FLATWARE

Roy E. Berg, Great Neck, N. Y., assignor to Tech-Art Plastics Company, a corporation of New Jersey

Application January 29, 1943, Serial No. 109,356

Term of patent 3½ years

To all whom it may concern:

Be it known that I, Roy E. Berg, a citizen of the United States, residing at Great Neck, in the county of Nassau and State of New York, have invented a new, original, and ornamental Design for a Spoon or Other Article of Flatware, of which the following is a specification, reference being had to the accompanying drawing, forming a part thereof.

Fig. 1 is a plan view of a spoon showing the essential features of my design in full lines; and

Fig. 2 is a cross-sectional view on line 2—2 of Fig 1 looking in the direction of the arrows, the back of the spoon handle being plain.

I claim:

The ornamental design for a spoon or other article of flatware, as shown and described.

ROY E. BERG.
